UNITED STATES PATENT OFFICE.

STILLMAN A. WEST AND CHARLES SINNING, OF ST. LOUIS, MISSOURI.

LEATHER-STRETCHING MACHINE.

SPECIFICATION forming part of Letters Patent No. 423,846, dated March 18, 1890.

Application filed April 6, 1889. Serial No. 306,254. (No model.)

To all whom it may concern:

Be it known that we, STILLMAN A. WEST and CHARLES SINNING, both of the city of St. Louis, in the State of Missouri, have invented a certain new and useful Improvement in Machines for Stretching Leather, of which the following is a full, clear, and exact description, reference being had to the accompanying drawings, forming part of this specification.

This machine is intended to stretch the edge of the upper of a boot or shoe at the shank before lasting.

Figure I is a side elevation of the machine, the table or stand being in vertical section. The shoe-upper is shown in position and the operator about to work the treadle. Fig. II is a transverse section of the treadle-lever at II II, Fig. I. Fig. III is a transverse section of the treadle-lever at III III, Fig. I. Fig. IV is a transverse section of the treadle-lever at IV IV, Fig. I. Fig. V is a side elevation of the machine with the jaws open ready to receive the work. Fig. VI is a longitudinal section of the machine at VI VI, Fig. VII. Fig. VII is a plan of the machine with the jaws open. Fig. VIII is a detail transverse section at VIII VIII, Fig. VII. Fig. IX is a detail transverse section through the central toggle-hinge at IX IX, Fig. VII. Fig. X is a transverse section of the machine at X X, Fig. VII. Fig. XI is a transverse section of the machine at XI XI, Fig. VII. Fig. XII is a detail plan showing the jaws closed upon the leather. Fig. XIII is a transverse section at XIII XIII, Fig. VII.

1 is the table or stand, to which the machine is secured by bolts or screws 2, which pass through the legs 3 into the table. 4 is the bed-piece of the machine, having standards 5 and 6, in whose bearings 7 slide the longitudinal rods 8. These rods carry at the front end a cross-head 9, firmly secured to the rods by pin 10. The cross-head carries one of the jaws, which is composed of a number of vertical edged teeth 11, between which are inclined recesses 12. The other jaw is upon a sliding head 13, which works on the rods 8 as guides. This jaw 13 has teeth 14,

whose front edges are inclined, as seen in Fig. VI, projecting farther at the top than at the bottom, so as to stretch the leather the most at the edge which is at top.

The central tooth 11' is a spring-tooth, having a square or splined shank 11², working in a socket in the jaw 9 and retained by a pin 11³.

11⁴ is a spiral spring, bearing against the shoulders 11⁵ and tending to hold the tooth 11' in its advanced position, as seen in Fig. VII. The spring, however, allows the retreat of the tooth in the position shown in Fig. XII, so as to relieve that part of the leather from a part of the strain which would otherwise come upon it. The part of the leather thus relieved is the point occupied by the seam between the quarter and vamp, and the purpose of relief is to prevent the opening or ripping of or-tearing of the leather at the seam. The seam is during the act of stretching held between the spring-tooth and a projection 14' of the plate 15, having a rounded recess 14², fitting the tooth 11'. It will be seen that the spring-tooth will force the seam into the recess and hold it with a moderated degree of pressure before the stretching action begins, so that the spring-tooth serves to assist in holding the leather in position. (See Figs. VI, VII, and XII.)

The teeth 14 are removable, so that teeth of different shape or size may be substituted. For this purpose they are upon a block 15, fitted to the cross-head 13 and attached thereto by screws 16.

17 are pins upon the ends of the cross-head 13, upon which are looped the front ends of the spiral draw-springs 18, whose other ends are looped upon the pins 19 upon the standard 6. The tendency of the springs is to draw the cross-head 13 to its rear position, as seen in Figs. I, V, and VII. In their movement forward and backward the teeth 14 work through an aperture in the standard. (See Fig. X.)

The cross-head has a rounded rib 20, which enters a rounded recess 21 of the standard 5 as the cross-head 9 moves backward and grips the leather, while the cross-head 13 is still at rest, so that when the latter moves forward

the part of the leather between the two points 20 shall be stretched by the overlapping teeth 11 and 14.

22 are adjustable guides for the leather in 5 its insertion between the jaws.

23 is a cross-bar upon the rods 8, secured thereto by pins 24. The cross-bar 23 and the cross-head 13 have similar bearings 25 for the rounded ends 26 of the toggle-bars 27. The 10 toggle-bar pintle 28 passes through a coupling-block 29, having a screw-socket 30, in which screws the upper end of the rod 31, connecting the pintle with the horizontal arm 32 of the treadle-lever, said lever being 15 fulcrumed at 33. The lever is made in two parts 34 35 with adjustable connection. The upper part 34 has a channel 36, in which fits the upper end of the lower part 35, having endwise movement in the channel, but locked 20 in position by a bolt 37, which passes through a bolt-hole in one part and longitudinal slot 38 in the other part. (See part 34, as shown.) The lower part 35 is shown with a rib 38, adding 25 to its stiffness and affording means to prevent the turning of the bolt 37, as the head of the latter is recessed, as seen in Fig. III, to receive the rib.

39 is the treadle, pressure upon which draws down the toggle from the position shown in 30 Fig. V. The descent of the toggle is limited by a stop-nut 40 upon the rod 31, which regulates the amount of stretch, as desired. (See Fig. VI.) Beneath the nut 40 is a rubber block 41.

35 42 are spiral springs surrounding the rods 8 between the standard 6 and the cross-bar 23. These springs thrust the cross-bar forward, and with it the rods 8 and cross-head 9. The springs 42 are weaker than the springs 40 18, so that the first movement of the parts on the depression of the toggle is to force the cross-head 9, rods 8, and cross-bar backward until the leather is firmly gripped at 11' 14' and 20 21, which will prevent the further 45 backward movement of these parts, the cross-head 13 then moving forward and completing the operation.

43 are collars on the rods 8, which limit their forward movement.

50 44 are set-screws in the collars.

We claim as our invention—

1. In a machine for stretching shoe-quarters, the combination of the two movable jaws having overlapping teeth 11 and 14, the ribs 55 20 on one jaw, and a standard 5, having recesses 21, all adapted to operate substantially as and for the purposes set forth.

2. In a machine for stretching shoe-quarters, the combination of the movable jaws having overlapping teeth 11 and 14, the toggle 60 with its ends 26 acting, respectively, upon the two jaws, and the springs 42 and 18, of differ-

ent strength, all constructed and adapted to operate substantially as set forth.

3. In a machine for stretching shoe-quarters, the combination of the movable jaws having overlapping teeth 11 and 14, the toggle with its ends 26 acting, respectively, on the two jaws, the springs 42 and 18, differing in strength, the standard having recesses 21, and 65 projections 20 upon the front jaw, all constructed and adapted to operate substantially as set forth.

4. In a machine for stretching shoe-quarters, the combination of the rods 8, sliding in 70 bearings, the cross head or jaw 9, fixed to the rod 8 and carrying teeth 11, the cross-bar 23, fixed to the rods, the cross-head 13, sliding on the rods and carrying teeth 14, the springs 18, acting on the cross-head 13, springs 42, of less 80 power than the springs 18, acting on the cross-bar, and the toggle with ends respectively acting on the cross-bar 23 and cross-head 13, substantially as and for the purpose set forth.

5. In a machine for stretching shoe-quarters, the combination of reciprocating jaws 85 having interlocking teeth 11 and 14, the latter being inclined on the edges, one of said jaws having a resilient tooth, substantially as and for the purpose set forth.

6. In a machine for stretching shoe-quarters, the combination of the two reciprocating jaws with overlapping teeth 11 and 14, the toggle acting to force the jaws toward each other, springs varying in strength and acting 95 to draw the jaws apart, and means for operating the jaws, substantially as and for the purpose set forth.

7. In a machine for stretching shoe-quarters, the combination of the jaws with teeth 100 11 and 14, springs 18 and 42, drawing them asunder, the toggle 27 28, drawing them together, and a treadle-lever connected with the pintle 28 of the toggle and having extensible part 34 35, substantially as set forth.

8. In a machine for stretching shoe-quarters, the combination of the two movable jaws 9 and 13, having overlapping teeth 11 and 14, the spring-tooth 11' on one jaw, and projection 14' on the other jaw, substantially as and 110 for the purpose set forth.

9. In a machine for stretching shoe-quarters, the combination of the moving jaw 9, having teeth 11, spring-tooth 11', and rib 20, the standard having the recesses 21, and the 115 moving jaw 13, having the teeth 14, and the projection 14', all substantially as and for the purpose set forth.

STILLMAN A. WEST.
CHARLES SINNING.
